KEY CONSTRUCTION

Herbert E. Brown, Detroit, Mich., assignor to
 Burroughs Adding Machine Company, Detroit,
 Mich., a corporation of Michigan

Application April 1, 1939, Serial No. 265,446

8 Claims. (Cl. 197—70)

This invention relates to key lever constructions and, more particularly, to a column selecting key suitable for use in calculating machines or the like.

5 Keys of this type are used in calculating machines and the like which employ traveling paper carriages and are used to set up column stops for controlling movements of the paper carriage. The Fettig application, Serial No. 112,197, filed

10 December 23, 1936, discloses such a machine in which keys of this type are used and the key of the present application is an improvement over the key shown in said prior application. As shown in the prior Fettig application, such keys

15 may also be used to initiate movement of the carriage, thus eliminating the necessity of depressing two keys, that is, a tabulating stop key and a motor key, for causing the carriage to tabulate to a desired columnar position.

20 It is highly desirable in keys of this nature that they be easily depressible and that they be positive in their movements, i. e., compelled to complete their movements from inactive to active position or vice versa, once the operator 25 starts the movement of the key.

Accordingly, it is a purpose of this invention to provide an improved key of this character.

It is a further object of this invention to provide a key of this character so constructed that, 30 upon depression, full movement thereof will be enforced.

It is a still further object of this invention to provide a key of this character which is readily adjustable to different positions, that is, one that 35 is readily removable from its supporting stop bar.

Further objects and their resultant advantages will be apparent from the following description given in connection with the drawing, in which

40 Figure 1 is a partial perspective of a portion of a carriage of a calculating machine illustrating two columnar selecting keys constructed in accordance with this invention, one key being in inactive position and the other being in active position;

45 Fig. 2 is an end elevation of a key lever constructed in accordance with this invention and associated parts. The key being shown in inactive position in full lines and in active as well as released position in dash-dot lines; and

50 Fig. 3 is an end elevation of a key lever and associated parts in depressed or active position.

Referring to the drawing, there is illustrated 55 a portion of a traveling paper carriage of a calculating machine comprising a portion of the left end frame 1 which supports cross bars 2

and 3 as well as the stop bar 4, the latter having a series of slots 6 in the upper side thereof, there being a slot for each letter space position of the carriage.

The key levers, two of which are shown in Fig. 1, are formed of two parts, i. e., each comprising an irregularly shaped upper key portion or stamping 7 provided with a key top or finger-piece 8 and a lower base portion or stamping 9, which is substantially U-shaped and adapted to 10 yieldingly and detachably engage the slotted stop bar 4, as clearly shown in the drawing. The two portions are pivotally connected at 11. The upper arm of the base portion which engages in the slots 6 of the bar 4 is formed with a pair of 15 downwardly extending projections 12 spaced apart the width of the bar, whereby the key levers are detachably retained upon the bar due to the natural resiliency of the U-shaped base portion, the lower arm of which is made relatively narrow 20 for this purpose. The base portion can be readily removed by rocking the key counterclockwise, exerting sufficient forward effort upon the key to spring the arms apart and slide the key off the bar, as will be explained later.

25 The upper key portion can be rocked about the pivot 11 to either its inactive or counterclockwise position or its active or clockwise position and is urged toward and retained in either 30 position by a pawl 15 pivoted at 16 to the upper key lever portion 7 and urged clockwise about its pivot by a spring 17. Spring 17 urges the lower edge of the pawl 15 into contact with the upper somewhat pointed end of the base portion 9 with the result that when the key is moved 35 counterclockwise from active to inactive position, the pawl tends to ride down the forward side of the end portion of the base under urge of spring 17. This forces the upper portion 7 counterclockwise to full inactive position once the key 40 has passed approximately its central intermediate point in moving from active to inactive position. The key is limited in its counterclockwise movement by engaging a U-shaped blade 45 20 attached to the form holder 21 which has a stud and slot connection 22 with the bar or bracket 2. The form holder is used to carry a strip of paper in which is marked the identification of the columnar position of the carriage.

Likewise, when the key is moved clockwise 50 from its inactive position toward its active position, the pawl 15 tends to ride down the rear side of the end of the base 9 once it has passed the central or intermediate point under urge of spring 17 which forces the key to its full active 55

position. When so moved, a rearwardly and downwardly projecting finger 25 of the key engages and rocks a bail 26 which raises a slide 27 which causes the stop 28 to be moved upwardly from the Fig. 2 to the Fig. 3 position, in which position it is retained by an abutment 29 overlying a block 30 as shown in Fig. 1. The carriage is then released for tabulation and moves to the left until the upper portion 1 of the depressed key engages the stop or slide 28 moving it slightly to the left until the abutment 29 clears the block 30. The stop then drops, lowering slide 27, which rocks the bail 26 and rocks the depressed key to inactive position. For further description of the foregoing mechanism, reference is made to the Fettig application heretofore mentioned and to the Thieme Patent No. 1,259,929.

Due to the fact that it is the key stem which actually releases the carriage tabulating mechanism and then serves as a stop for limiting movement of the carriage, it is very necessary that full movement of the key to either active or machine position be enforced or compelled and this is accomplished by the foregoing mechanism. It will be apparent that it is only actually necessary for the key to be depressed partially to move it either to the active or inactive position, after which the spring-urged pawl 15 will insure full and complete movement of the key lever to either its inactive or active position where it will be retained until returned.

In order to facilitate removal and readjustment of the key levers to other columnar positions on the stop bar 4, the upper portion 1 of the key lever is provided on its lower edge with a cam-like shoulder 31 (Fig. 2) which, when the key is rocked counterclockwise beyond its normal inactive position, engages the upper surface of the stop bar 4 and spreads the arms of the base portion to cause the rear lug 12 to clear the stop bar and permit ready removal of the key. It will be understood, of course, that the form holder 21 and U-shaped blade 20 will have been removed. The key lever can then, of course, be readily installed in a new position along the slotted stop bar 4.

From the foregoing description, it will be apparent that there has been provided a very simple key lever construction which not only insures proper movement of the key to either active or inactive position, but permits ready removal and reinsertion of the key, thus facilitating adjustment of the key to different columnar positions along the supporting stop bar.

It will also be apparent to those skilled in the art that the key lever may be applied to different types of machines and that minor changes may be made in the details of construction of the parts without departing from the spirit and scope of the invention as defined in the appended claims.

I claim:

1. A columnar selecting key for use in calculating and the like machines having a traveling carriage and tabulating means therefor including an element cooperating with said key, said key comprising a base portion adapted to detachably engage a stop bar in a selected one of a plurality of positions, a key portion pivoted to said base portion and movable about said pivot from an inactive position to an active position for cooperation with said element of said tabulating means, and reversely, and resilient means for urging said key portion away from a position intermediate said active and inactive posi-

tions to either said active or said inactive position in the direction of its last movement past said intermediate position.

2. A columnar selecting key for use in calculating and the like machines having a traveling carriage and tabulating means therefor including an element cooperating with said key, said key comprising a base portion adapted to detachably engage a stop bar in a selected one of a plurality of positions, a key portion pivoted to said base portion and movable about said pivot from an inactive position to an active position for cooperation with said element of said tabulating means and reversely, a cam on one of said portions, and a spring urged pawl on the other of said portions cooperating with said cam to urge said key portion away from a position intermediate said active and inactive positions to either said active or said inactive position.

3. A columnar selecting key for use in calculating and the like machines having a traveling carriage and tabulating means therefor including an element cooperating with said key, said key comprising a base portion adapted to detachably engage a stop bar in a selected one of a plurality of positions, a key portion pivoted to said base portion and movable about said pivot from an inactive position to an active position for cooperation with said element of said tabulating means and reversely, a cam on said base portion, and a spring urged pawl carried by said key portion and cooperating with said cam to urge the latter away from a position intermediate said active and inactive positions to either said active or said inactive position.

4. A columnar selecting key for use in calculating and the like machines having a traveling carriage and tabulating means therefor including an element cooperating with said key, said key comprising a base portion adapted to detachably engage a stop bar in a selected one of a plurality of positions, a key portion pivoted to said base portion and movable about said pivot from an inactive position to an active position for cooperation with said element of said tabulating means and reversely, a cam on one of said portions, and a spring urged pawl pivoted to the other of said portions and cooperating with said cam to urge said pivoted key portion in either direction away from a position intermediate said active and inactive positions.

5. A columnar selecting key for use in calculating and the like machines having a traveling carriage and tabulating means therefor including an element cooperating with said key, said key comprising a base portion adapted to detachably engage a stop bar in a selected one of a plurality of positions, a key portion pivoted to said base portion and movable about said pivot from an inactive position to an active position for cooperation with said element of said tabulating means and reversely, a cam on said base portion, and a spring urged pawl pivoted to said key portion and adapted to engage said cam and urge said key portion away from a position intermediate said active and inactive positions to one or the other of said active or inactive positions.

6. A columnar selecting key for use in calculating and the like machines having a traveling carriage, tabulating means therefor including an element cooperating with said key, and a slotted stop bar, said key comprising a substantially U-shaped base portion adapted to yieldingly and detachably engage said slotted stop bar in any

- one of a plurality of positions, a key portion pivoted to said base portion and movable about said pivot from an inactive position to an active position for cooperation with said element of said 5 tabulating means and reversely, with means on said key portion adapted, when said key portion is moved beyond one of said positions, to cooperate with said stop bar to release the base portion from said stop bar.
- 10 7. A columnar selecting key for use in calculating and the like machines having a traveling carriage, tabulating means therefor including an element cooperating with said key, and a slotted stop bar, said key comprising a substantially 10 U-shaped base portion adapted to yieldingly and detachably engage said slotted stop bar and a key portion pivoted to said base portion and movable about said pivot from an inactive position to an active position for cooperation with said 15 element of said tabulating means and reversely, with cam means on said key portion adapted, when said key portion is moved beyond one of said positions, to cooperate with said stop bar to spread said U-shaped base portion to release said 20 base portion from said stop bar.
- 25 8. A columnar selecting key for use in calculating and the like machines having a traveling carriage, tabulating means therefor including an element cooperating with said key, and a slotted stop bar, said key comprising a substantially 5 U-shaped base portion adapted to yieldingly and detachably engage said slotted stop bar and a key portion pivoted to said base portion and movable about said pivot from a normal inactive position to an active position for cooperation with 10 said element of said tabulating means and reversely, resilient means for urging said key portion away from a position intermediate said active and inactive positions to one or the other 15 of said active or inactive positions, said resilient means permitting manual movement of said key portion beyond said normal inactive position, and means on said key adapted, when said key portion is moved beyond said normal inactive position, to cooperate with said stop bar to spread 20 said U-shaped base portion to release said base portion from said stop bar.
